(57) **CLAIM**

The ornamental design for a mailer having a check component and an address correction component, as shown and described.

DESCRIPTION

FIG. 1 is a front perspective view of a first embodiment of a foldable mailer having a check component and an address correction component, the mailer shown in an unfolded condition;

FIG. 2 is a back perspective view of the first embodiment of the foldable mailer having the check component and the address correction component, the mailer shown in an unfolded condition;

FIG. 3 is a front perspective view of the first embodiment of the foldable mailer having the check component and the address correction component, the mailer shown in a folded condition;

See application file for complete search history.

FIG. 4 is a back perspective view of the first embodiment of the foldable mailer having the check component and the address correction component, the mailer shown in a folded condition;

FIG. 5 is a front perspective view of a second embodiment of a foldable mailer having a check component and an address correction component, the mailer shown in an unfolded condition;

FIG. 6 is a back perspective view of the second embodiment of the foldable mailer having the check component and the address correction component, the mailer shown in an unfolded condition;

FIG. 7 is a front perspective view of the second embodiment of the foldable mailer having the check component and the address correction component, the mailer shown in a folded condition; and,

FIG. 8 is a back perspective view of the second embodiment of the foldable mailer having the check component and the address correction component, the mailer shown in a folded condition.

The broken lines represent physical perforations in the mailer. The portions of the disclosure shown in broken dash-double-dot lines represent structural environment and form no part of the claimed design.
